CLAIM

The ornamental design for a combined automotive air
pump, vacuum cleaner and dispensing unit for anti-
freeze and air freshener, as shown.

DESCRIPTION

FIG. 1 is a front-elevational view of a combined auto-
motive air pump, vacuum cleaner and dispensing unit
for antifreeze and air freshener showing our new de-
sign;

FIG. 2 is a right side elevational view thereof;

FIG. 3 is a bottom plan view thereof;

FIG. 4 is a rear elevational view thereof;

FIG. 5 is a left side elevational view thereof;

FIG. 6 is a top plan view thereof.
